(57) **CLAIM**

The ornamental design for a computer desk, as shown and described.

DESCRIPTION

FIG. 1 is a front, right and top perspective view of a computer desk, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view thereof, shown in an alternative position, wherein the desktop is shown raised; and,

FIG. 10 is another perspective view thereof, shown in an alternative position, wherein the desktop is shown raised. The broken lines shown in the drawings illustrate portions of the computer desk that form no part of the claimed design.

1 Claim, 10 Drawing Sheets
